(21) Appl. No.: **29/097,411**

(74) Attorney, Agent, or Firm—Dougherty & Clements
LLP

(22) Filed: **Dec. 7, 1998**

(57) **CLAIM**

(51) LOC (7) Cl. **15-03**

The ornamental design for a fluid distributing bar for a
rotatable wet mower blade, as shown and described.

(52) U.S. Cl. **D15/17**

DESCRIPTION

(58) **Field of Search** D15/10, 14-17,
D15/28; 56/11.9, 16.7, 17.1, 17.5, 202,
255, 295; 239/276

FIG. 1 is a perspective view of the fluid distributing bar for
a rotatable wet mower blade showing the new design;
FIG. 2 is a back view of the fluid distributing bar for a
rotatable wet mower blade showing the new design;
FIG. 3 is a left side view thereof;
FIG. 4 is a top view thereof;
FIG. 5 is a right side view thereof;
FIG. 6 is a front view thereof; and,
FIG. 7 is a bottom view thereof.
